UNITED STATES PATENT OFFICE.

JOHN LOW ZACHRY, OF ATLANTA, GEORGIA.

WATER-HEATER.

1,312,012.

Specification of Letters Patent. Patented Aug. 5, 1919.

Application filed April 25, 1918. Serial No. 230,777.

To all whom it may concern:

Be it known that I, JOHN LOW ZACHRY, a citizen of the United States, and a resident of Atlanta, in the county of Fulton and State of Georgia, have invented certain new and useful Improvements in Water-Heaters, of which the following is a specification.

My invention is an improvement in water heaters, and has for its object to provide a heater of the instantaneous type, wherein a casing for water is provided, having a central flue within which is spirally arranged a pipe for supplying water, the pipe communicating with the casing near the top thereof and the casing having a burner at the bottom of the flue for heating the water as it flows through the coil.

In the drawings:

Figure 1 is a vertical section of one embodiment of the invention; and

Fig. 2 is a similar view of another embodiment.

In the embodiment of the invention shown in Fig. 1, a casing 1 is provided, having a central flue 2 which extends from near the bottom of the casing to and through the top 3 of the casing. This flue, as shown, tapers from below upward, and has a reduced portion which extends through the top. A water chamber is thus formed between the flue and the interior of the casing, and this chamber has a discharge pipe 4 near its top. The water is supplied to the casing from a pipe 5, which passes into the casing below the connection of the flue therewith, and the pipe then passes upwardly, as indicated at 6, along the inner face of the flue wall, following the said wall to near the reduced portion. The pipe then becomes spiral and the coils 7 of the spiral, which are spaced apart from each other, extend toward the bottom of the casing, where the pipe passes out opposite the point it entered. The pipe then passes upwardly outside of the casing, as indicated at 8, and connects with the casing below the discharge by an elbow 9. A valve 10 is interposed in the pipe 5 just before it enters the casing, and a heater 11 is arranged at the bottom of the casing. In the present instance the heater is a ring having an outwardly offset portion 12 within which the casing seats.

In the embodiment of the invention shown

in Fig. 2, the casing 13 has the closed top 14, and the flue 15 is continuous at its bottom 55 with the bottom of the casing 13. This flue, which is of the same type as that shown in Fig. 1, passes out at the top of the casing, and at its lower end the casing has a ring 16 which seats in a base 17, the base having 60 an outwardly offset portion similar to that 12 of the ring 11. A burner 18 is arranged below the bottom of the flue, within the ring 16, and the water pipe 19—20—21—22, which is arranged in the same manner as the pipe 65 5—6—7—8, communicates with the water chamber near the bottom of the said chamber, as shown, instead of near the top. The casing 13 has a discharge 23 at its top and in both constructions a baffle 24 is arranged 70 within the spiral portion of the pipe just below the base portion of the flue. This baffle, which is frustro-conical, has its large end upward, and the said large end is of slightly greater diameter than the interior 75 of the reduced portion of the flue. This large end is spaced below the reduced portion of the flue slightly, so that the heated air may pass between the flue wall and the large end of the baffle. The baffle is for the 80 purpose of spreading the heated air and deflecting it on to the spiral portion of the pipe and on to the flue wall at the top.

In operation, when heated water is required, the burner is lighted, and as the 85 water is drawn from the casing, the inflowing water must pass through the spiral, thus becoming heated before its entry into the water chamber. It is further heated here by its contact with the flue wall, and the 90 water will very quickly become hot enough for use. The water in the water chamber is in a comparatively thin layer and is easily heated.

I claim:

A water heater comprising a substantially cylindrical casing having a central flue extending from near the bottom of the casing through the top thereof and spaced apart from the wall of the casing to form a water 100 chamber of relatively small thickness, said central flue being connected to the wall of the casing at its lower end, a water supply pipe extending into the casing below the flue from one side and out at the other side and 105 having a spiral portion within the flue ex-

tending from the bottom to near the top thereof, the coils of the spiral being spaced apart from each other and from the wall of the flue, and the said pipe opening into the 5 water chamber, a heater at the bottom of the casing, and a baffle at the top of the spiral,

the flue having a reduced portion at its upper end just above the baffle.

JOHN LOW ZACHRY.
